UNITED STATES PATENT OFFICE

CHARLES ADLER, JR., OF BALTIMORE, MARYLAND

DESIGN FOR A TRAFFIC SIGNAL FACING

Application filed July 23, 1931. Serial No. 40,842. Term of patent 14 years.

To all whom it may concern:

Be it known that I, CHARLES ADLER, JR., a citizen of the United States, residing at the city of Baltimore and State of Maryland, have invented a new, original, and ornamental Design for Traffic Signal Facing, of which the following is a specification, reference being had to the accompanying drawing, forming a part thereof.

The figure is a front elevation of the traffic signal facing and is lined for color. The device is relatively thin with respect to its other dimensions.

My signal facing is adapted for use as a traffic signal and the dominant feature of my design consists of a plurality of signal elements, the end elements being of substantially rectangular form having curved ends, and arranged at substantially right angles to each other.

I claim:

The ornamental design for a traffic signal facing as shown and described.

CHARLES ADLER, JR.
